Primary Examiner — Selina Sikder(74) *Attorney, Agent, or Firm* — Panasonic IP Management; Kerry S. Culpepper(57) **CLAIM**

The ornamental design for a dimmer switch, as shown and described.

DESCRIPTION

FIG. 1 is a front perspective view of a dimmer switch of the present invention;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken line showing of dimmer switch is included for the purpose of illustrating environment and forms no part of the claimed design.
